(57) **CLAIM**

The ornamental design for a rooftop tent, as shown and described.

DESCRIPTION

FIG. 1 is a front and top perspective view of a rooftop tent design showing my new design.

FIG. 2 is a rear and bottom perspective view of a rooftop tent.

FIG. 3 is a front view of a rooftop tent, shown enlarged in scale.

FIG. 4 is a rear view of a rooftop tent, shown enlarged in scale.

FIG. 5 is a left side view of a rooftop tent.

FIG. 6 is a right side view of a rooftop tent.

FIG. 7 is a top view of a rooftop tent.

FIG. 8 is a bottom view of a rooftop tent.

FIG. 9 is an enlarged partial view of a top corner of the rooftop tent taken from encircled area 9 in FIG. 3.

FIG. 10 is an enlarged partial view of a middle part of the rooftop tent taken from encircled area 10 in FIG. 3; and, FIG. 11 is an enlarged partial view of the rooftop tent taken from encircled area 12 in FIG. 2.

Any shading and cross-hatching are not features of the design but are utilized to illustrate the surface contours of the rooftop tent design in the drawings.

The shade lines shown in the drawings represent the three-dimensional contours of the rooftop tent and are not intended to indicate surface decoration.

The broken-lined circles are included to annotate partial views in FIGS. 2, 3 and 9-11. All other broken lines represent portions of the rooftop tent that form no part of the claimed design. None of the broken lines form a part of the claim.
